CONVERTIBLE SEAT AND TABLE ASSEMBLY

Clyde E. McCaw, Coeur d'Alene, Idaho

Application December 18, 1945, Serial No. 635,625

3 Claims. (Cl. 155—43)

1

This invention relates to a combination lawn table and bench, so constructed that the table top may be associated with the bench as a back rest therefor.

It is an object of the invention to provide a lawn table and bench, of rugged and durable construction, and the table having a pivotally mounted table top, which may be pivoted into proper relation with respect to the bench to form a back rest for the bench.

It is a further object of the invention to provide a combination bench and table, capable of being converted to a bench with back rest, which shall be especially rugged and sturdy in either form, and which shall be particularly adapted for picnic outings, camping, pleasure resorts and the like.

The above and further objects of the invention will become apparent upon study of the following specifications when taken in conjunction with the accompanying drawings, wherein:

Figure 1 is a front elevational view of an embodiment of the invention;

Figure 2 is an end view of Figure 1, partly in section, to show a detail; and

Figure 3 is a vertical sectional view of the detail of a pivot and locking key arrangement.

Reference is now had to the figures of the drawings, wherein the same numerals are applied to like parts, in the several views.

Numerals 1 represent a table top, secured to the under surface of which are two cross braces 2, each adjacent to an end of the table top and extending from the front to the rearward edges of the table top. The cross braces 2 are beveled adjacent the forward ends thereof, as indicated by the numeral 3.

Extending perpendicularly from the cross braces are depending supports 4, each support 4 being secured to a cross brace 2 adjacent the center of its lower surface.

The supports 4 are pivotally secured to the upper end portions of a pair of upright legs 5, by respective bolts 6 one of which extends through each support 4 and its associated leg 5, and which are threaded to receive nuts 7. Washers 8 are interposed between the nuts and the corresponding supports 4 and between the bolt heads and legs 5.

The legs 5 rest on horizontal base supports 9 and are rigidly secured thereto by right angled brackets 10, suitably bolted to both the supports 9 and the legs 5. A cross brace 11 extends between the legs 5 at the rearward edges thereof and rests on portions of horizontal supports 9,

said cross brace 11 being secured by any suitable means to the legs 5 and to the supports 9.

An elongated seat 12 is supported by cross legs 13, 14, legs 13 extending downwardly and rearwardly from the forward edge of the seat 12, and the legs 14 extending forwardly and downwardly from the rearward edge of the seat 12. The legs 13 are secured to the horizontal supports 9 on their outer surfaces and the legs 14 are secured to the supports 9 on their inner surfaces.

Each pair of cross legs 13 and 14 are separated at their cross over point by the width of the support 9, and are braced at a point immediately under the seat 12 by a trapezoidal brace 15 which may be secured at its upper edge to the seat 12, and which, having slant sides flush with the outer edges of the legs 13, 14 of each pair of legs may be secured thereto by any suitable means.

Additional bracing is provided for the inner legs 14 which are provided with a cross brace 16 secured to each leg 14 by a pair of angle irons 17. The seat is thus supported in fixed relationship to said pair of upright legs with its end edge spaced from and substantially parallel thereto.

The supports 4, which are pivotally secured to legs 5 by means of bolts 6, are normally prevented from pivoting by keys 18 extending through both supports 4 and legs 5, in registering apertures provided for that purpose. The keys 18 are constructed in the form of metal rods having ring ends.

When it is desired to convert the table top 1 into a back rest for the seat 12, the keys 18 are removed from the registering apertures in the legs 5 and the supports 4 and are inserted in suitable apertured receptacles 19 provided on the cross braces 2, with a portion of the rod ends of the keys 18 extending beyond the forward edge of the table top 1.

Provided in the seat 12 are two holes 20 extending from the rearward upper edge of the seat 12, downwardly and forwardly at an angle of about 60° with the horizontal, although this angle is not critical and may be varied as other dimensions are varied, such as the width of the table top 1, the width of the seat 12 and the spacing between the seat and table top, both vertically and horizontally. The holes 20 receive the rod ends of keys 18 and thereby serve to lock the table top 1 to the seat 12, in proper position to form a back rest for said seat 12.

Having described a preferred embodiment of the invention, it is to be understood that various dimensions, arrangements, combinations and expedients utilized therein may be modified without

departing from the spirit of the invention and that I desire to be limited only by the scope of the appended claims.

What I claim is:

1. A convertible seat and table assembly comprising a pair of spaced apart base supports, a pair of upright legs extending respectively upwardly from said base supports at corresponding ends thereof, a pair of crossed-legs extending upwardly from each base support, a seat secured to the upper ends of said pairs of crossed-legs and spaced from said upright legs, a table top, a pair of depending supports secured to the underside of said table top one adjacent each end thereof, means pivotally connecting each of said depending supports to the upper end portion of a corresponding upright leg for movement of said table top between a generally horizontal position upon the upper ends of said upright legs and a position in which its lower edge contacts the inner edge of said seat and it inclines upwardly toward the upper ends of said upright legs to constitute a back for said seat, means operatively associated with said upright legs and said table top to releasably lock said top in said generally horizontal position, and releasably connecting the lower edge of said top to the inner edge of said seat when said top is in said inclined position.

2. A convertible seat and table assembly comprising a pair of spaced apart upright legs, an elongated seat, means supporting said seat and said pair of upright legs in fixed, spaced apart position relative to each other, a table top, means pivotally securing said top to the upper ends of said upright legs for movement between a generally horizontal position and an inclined position in which its lower edge rests upon the inner edge of said seat and it constitutes a back for said seat, means operative to releasably lock said

top to said upright legs in said generally horizontal position, and means operative to releasably connect the contacting edges of said seat and top when said top is in said inclined position.

3. A convertible seat and table assembly comprising a pair of spaced apart upright legs, an elongated seat, means supporting said seat and said pair of upright legs in fixed, spaced apart position relative to each other, a table top, means pivotally securing said top to the upper ends of said upright legs for movement between a generally horizontal position and an inclined position in which its lower edge rests upon the inner edge of said seat and it constitutes a back for said seat, means operative to releasably lock said top to said upright legs in said generally horizontal position, and means operative to releasably connect the contacting edges of said seat and top when said top is in said inclined position, said locking means for said top and said upright legs and for said top and said seat including a common pair of locking pins.

CLYDE E. McCAW.
